CORNER MOUNTING BRACKET FOR A MOBILE HOME TIE DOWN SYSTEM Milton J. Miller, 39 Greenway Drive,
Goshen, Ind. 46526

Filed Sept. 17, 1973, Ser. No. 397,858

Term of patent 14 years

Int. Cl. D8—08

U.S. Cl. D8—229

Fig. 1**Fig. 3****Fig. 2****Fig. 4**

FIG. 1 is a perspective view of a corner mounting bracket for a mobile home tie down system, embodying the present design;

FIG. 2 is an elevational view of the end of the corner mounting bracket, opposite the end shown in FIG. 1;

FIG. 3 is a side elevational view of the corner mounting bracket shown in the preceding figures, the view being the side opposite that shown in FIG. 1; and

FIG. 4 is a top plan view of the corner mounting bracket shown in the preceding figures.

I claim:

The ornamental design for a corner mounting bracket for a mobile home tie down system, substantially as shown.
